UNITED STATES PATENT OFFICE.

ERNEST J. QVARNSTROM, OF ATTLEBORO, MASSACHUSETTS.

POCKET COMB.

1,414,042.

Specification of Letters Patent. Patented Apr. 25, 1922.

Application filed November 7, 1921. Serial No. 513,537.

To all whom it may concern:

Be it known that I, ERNEST J. QVARNSTROM, a citizen of the United States, residing at Attleboro, in the county of Bristol and State of Massachusetts, have invented certain new and useful Improvements in Pocket Combs, of which the following is a specification.

This invention relates to pocket combs in which a comb is adapted to be housed in a casing when not in use and to be moved outwardly causing its teeth to project from the casing ready for use when desired, and the object of this invention is to provide a practical construction for such a comb in which a shoe member is mounted in the case and is adapted to embrace both sides of the comb, the same being provided with inclined slots into which guides on the comb are adapted to fit whereby a longitudinal movement of the operating member moves the comb outwardly, and a movement in the reverse direction withdraws the comb back into its case to house the same and protect it while in the pocket of the wearer.

With these and other objects in view, the invention consists of certain novel features of construction, as will be more fully described, and particularly pointed out in the appended claims.

In the accompanying drawings,

Figure 1 is a perspective view showing a comb-case in which a comb is housed.

Figure 2 is a perspective view showing the comb as extending from the case, in which position the case serves as a convenient operating handle.

Figure 3 is a side elevation showing the case in section and illustrating the comb as housed therein and embraced by its operating shoe.

Figure 4 is a perspective view of the comb removed and showing the two sets of guide pins in its back to engage the inclined slots in the shoe-member.

Figure 5 is an edge view of the comb showing the shoe in section and embracing both sides of the comb.

Figure 6 is a perspective view of the shoe.

Figure 7 is a perspective view of the thumb-piece operating member removed.

Figure 8 is a perspective view of the cap of precious metal which is adapted to be fitted over and connected to the exposed end of the operating member.

Figure 9 is a sectional side elevation of

the cap as applied to the operating member to operatively connect the shoe to the casing.

Figure 10 is a sectional end view showing the comb extended and the inturned edges of the case serving as sliding guides for the shoe.

With reference to the drawings, 10 designates a comb case which is preferably constructed of a size to be conveniently carried in the pocket and made of or plated with precious metal, the same being adapted to be highly ornamental to render it attractive in appearance, and it may be provided with 15 a bail 11 at one end if desired, to be connected to the end of a watch chain.

The upper edge of this case is preferably slotted longitudinally as at 12 for the reception of a thumb-piece or operating member, presently described. Within this casing is mounted a shoe member 13 adapted to slide longitudinally therein, the same being folded into U-shape in cross section so as to embrace both sides of the comb 14 when set therein. Both of the side walls of this shoe are provided with a pair of inclined slots 15 which have a longitudinally-extending portion 16 at their lower ends and the comb is provided with guide pins 17 extending into both slots in both side walls of the shoe whereby the comb is accurately guided and so easily moved inward and outward relative to the casing when the shoe is moved longitudinally thereof.

When the comb is extended the maximum distance from its casing its guide pins 17 enter the longitudinal portions of the slots 16 which serve to prevent the comb from being forced back into its case when under endways pressure in operating.

In order to connect this shoe member with its comb to the case, I have provided a thumb-piece or operating member 18 which is provided with inner edge flanges 19. This member is passed from the inside outwardly through an opening 20 in the back of the shoe to extend out through the slot 12 in the casing, a washer 21 is then placed over this member to rest upon the outer surface of the casing, and a cap member 22 which is preferably formed of or plated with precious metal is forced down over and caused to grip the end of this operating member to perform two functions; first, it covers and incloses the base metal of this member within the envelop of precious metal; and sec-

ond, by forcing its ends inwardly into the notches 23 in this member it is locked thereonto and its lower edges 24 engage and secure the washer 21 in position on the outer 5 face of the casing thereby operatively securing the shoe 13 in the casing 10 so that a longitudinal movement of this member along the casing serves to impart a corresponding movement to the shoe and a right angle 10 movement to the comb to extend it beyond the casing and when moved in the opposite direction to withdraw it and house it in the casing.

I also preferably turn the free edges of 15 the case inwardly as at 25, see Figure 10, to serve as a sliding guide for the outer edge of the shoe 13.

By securing this shoe against the inner wall of the casing I completely close the 20 slot 12 in the casing excluding foreign matter therefrom.

The device is by my improved construction 25 extremely simple and practical in its operation and by providing a shoe which is U-shaped in cross section to engage the operating pins on both sides of the comb, the comb is caused to operate easily in its casing without binding or cramping and also by providing a thumb piece or operating member 30 to extend from the back outwardly through the slot 12 it may be produced at the minimum expense and yet be very strong and durable.

The foregoing description is directed solely 35 towards the construction illustrated, but I desire it to be understood that I reserve the privilege of resorting to all the mechanical changes to which the device is susceptible, the invention being defined and limited only 40 by the terms of the appended claims.

I claim:

1. A device of the class described comprising 45 a case, a shoe U-shape in cross section fitted to slide endways in said case and having two sets of parallel-inclined slots through both of its side walls, a comb mounted between the side walls of said shoe and having guide pins extending laterally from both side faces thereof to engage the opposite

slots in both side walls of said shoe, and an 50 operating member connected to said shoe extending out through said case whereby an endways movement of said member in opposite directions moves the comb outward and inward relative to its case. 55

2. A device of the class described comprising 60 a case having a longitudinally-disposed slot through its upper edge, a shoe U-shape in cross section fitted to slide endways in said case and having an opening 65 registering with said slot, a separate operating member having an inner flange secured to said shoe and having a portion extending out through its opening and said slot and a comb operatively mounted between the side 70 walls of said shoe having guide pins extending laterally from both side faces thereof and engaging the opposite slots in both side walls of said shoe whereby a movement of said operating member moves said shoe endways to either raise or lower the comb in its case. 75

3. A device of the class described comprising 80 a case having a longitudinally-disposed slot through its upper edge, a shoe U-shape 75 in cross section fitted to slide endways in said case and having an opening registering with said slot, an operating member in said shoe having a flange on its inner end and extending outwardly through said opening in 85 said shoe and slot in said case, the outer edges of said member being notched, a washer on said member bearing on the outer 90 face of said case, a thin metal cap set over said member and secured thereto by being set into said notches, said shoe having inclined guide slots in both of its side walls and a comb operatively mounted between the side walls of said shoe having guide pins extending laterally from both side faces thereof and engaging the opposite slots in both 95 side walls of said shoe whereby a movement of said operating member moves said shoe endways to either raise or lower the comb in its case. 95

In testimony whereof I affix my signature.

ERNEST J. QVARNSTROM.
